UNITED STATES PATENT OFFICE.

FREDERICK SANFORD SEYMOUR, OF MANCHESTER, IOWA.

STOCK-WATERER.

SPECIFICATION forming part of Letters Patent No. 763,331, dated June 21, 1904.

Application filed August 26, 1903. Serial No. 170,828. (No model.)

To all whom it may concern:

Be it known that I, FREDERICK SANFORD SEYMOUR, a citizen of the United States, and a resident of Manchester, in the county of 5 Delaware and State of Iowa, have invented a new and Improved Stock-Waterer, of which the following is a full, clear, and exact description.

This invention relates to certain improvements in apparatus for containing an automatically-regulated supply of drinking-water for live stock, particularly on farms, but also in towns, villages, and in such other places as it may be desirable to care for the 15 stock.

By means of my invention the water is kept clean and free from the effects of the temperature, thus keeping the water cool in summer and preventing freezing in winter. The invention resides in certain special features of construction and arrangement of parts, as will hereinafter be fully set forth.

This specification is an exact description of one example of my invention, while the claims 25 define the actual scope thereof.

Reference is to be had to the accompanying drawings, forming a part of this specification, in which similar characters of reference indicate corresponding parts in all the views.

Figure 1 is a vertical section of the bowl and its appurtenances. Fig. 2 is a sectional plan on the line 2 2 of Fig. 1, and Fig. 3 is an elevation of the entire apparatus.

10 indicates the bowl, which may be of any 35 desired size and shape, but which is preferably circular, with conical top and bottom ends, as shown. The conical bottom end of the bowl is connected to or formed integral with a hollow column 11, forming an extension of the 40 bowl and projecting downwardly therefrom, the lower end of said column having a hollow enlargement 12, and these parts 10, 11, and 12 constitute the receiver for the water. The top 14 of the bowl is adapted to be removed 45 and is formed with orifices, as shown, so that the stock may reach the water within the bowl. Inside of the bowl is arranged a heating-chamber 15, which extends around the inner side walls thereof, and, as best shown in 50 Fig. 2, one end of said chamber opens later-

ally into a connection 16, while the other end has an upwardly-disposed outlet-flue 17, which has connection at its upper end with a flue 18, formed in or secured to the top 14 for a purpose which will be hereinafter fully set forth. 55

The connection 16 may be of any suitable construction, and it serves the double purpose of conducting hot air into the heating-chamber 15 and of supporting the cylindrical case 19. This case is constructed of non-conducting material in any suitable manner and has a removable top 20, formed with a dead-air chamber 21 to prevent loss of heat from the interior of the case 19. In this case a heating device of any suitable kind may be placed. 65 I prefer and have illustrated in the drawings an ordinary oil-lantern 22 for the reason that this is easier to handle and not liable to be extinguished by any means. The case 19 is further supported by a bracket 23, which is fastened to the case and projects laterally into engagement with the column 11. Air is supplied to the bottom of the case 19, so as to supply oxygen to the flame of the lantern by means of a branch 24, passing from a pipe 25, 75 which extends from the upper portion of the bowl 10 downwardly into communication with the atmosphere. The pipe 25 serves, therefore, not only to conduct air into the case 19 to support combustion, but also as an overflow or drain-pipe for the bowl 10. The case 19 has openings 19^a, which serve also to supply air to the interior of the case; but the main supply of air is through the upper end of the pipe 25. 80

The water-supply pipe 26 passes from any suitable source upward through the bottom of the column 11 into the lower portion of the bowl 10, where it is provided with a T-joint and branch 27, the latter terminating in a 90 valve 28, which may be of any desired construction, but which is preferably what is known commercially as a "diamond" valve. This valve is opened to control the flow of water from the branch 27, and it is actuated by 95 an arm 29, attached to the valve and connected with a rod 30, extending vertically and carrying at its upper end a float 31. The float is fastened to the rod 30 by means of a set-screw 32, and a rubber or other elastic cushion 33 is pro- 100

vided to increase the friction between the parts at this point. The float is therefore adjustable on the rod and the lower end of the rod preferably is forked or otherwise constructed so that the parts 29 and 30 may be relatively adjusted. Fastened to the top 14 of the bowl 10 is the upper section 34 of the float-shield, this section being cylindrical and open at its lower end and having the cylindrical lower float-shield section 35 removably fastened thereto by any desired means. The lower section 35 projects downward and is formed at its lower end with a longitudinal slot receiving the arm 29 and permitting the free movement thereof. This shield incloses the float and its rod and prevents these parts from being disturbed by the animals as they drink from the bowl. The before-mentioned flue 18 leads into the upper section 34 of the float-shield, and this section is formed with orifices 34^a, through which the gases from the flue 18 may reach the atmosphere.

A dirt-collector is provided to collect dirt in the bottom of the bowl, this collector being in the form of a tube 36, fitted in the upper end of the column 11 and projecting upward considerably above the same. 37 indicates handles which facilitate the removal of the tube 36, and 38 indicates a nipple formed in the tube for the passage of the branch pipe 27, this nipple being packed with cotton or other similar material, as illustrated. A conical gauze of woven-wire top 39 is provided for the tube 36, so that the water may have free passage into and out of the tube; but dirt and litter will be detained.

In the practical employment of the invention I sink the column 11 and its enlarged lower end 12 in the earth, so that the bowl 10 alone projects above the surface, in the manner illustrated in Fig. 3. I then build around the bowl a suitable curbing 40, provided with a cover 41 and having a removable wall, so that the interior of the curbing may be conveniently reached. Within the curbing I place a quantity of barnyard litter, straw, and the like, which surrounds the column 11 and the bowl 10 and not only protects these parts from the influences of the weather, but actually generates a certain amount of warmth. In the summer this material within the curbing may be replaced by mere earth, so as to keep the water cool. The water flowing from the valve 28 fills the bowl 10, the float 31 automatically operating the valve to cut off the water flow when a certain elevation of water has been reached within the bowl. This therefore maintains the water at a constant elevation and the stock may drink therefrom through the orifices in the cover 14. The water circulates through the bowl and column, the cold water ascending into the column, where it is there warmed from the earth, and thence returns into the bowl, thus giving the water the natural temperature of the earth.

During extremely cold weather the lantern or heating device should be placed within the case 19, and then the hot gases generated will pass through the connection 16 and circulate around the chamber 15 and pass thence through the flues 17 and 18 to the float-shield. This heats the whole body of water in the bowl, and particularly heats the water within the float-shield, so that it is practically impossible for the water to freeze and clog the movements of the float.

This invention is designed as an improvement over the structures shown in my prior patent, No. 661,622, dated November 13, 1900, and in my copending application, Serial No. 124,929, filed September 26, 1902, and the foregoing description, in connection with the prior art and the application, will make clear the purpose, use, and advantages of the present invention.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent —

1. The combination of a bowl, a column in communication with the bottom thereof, a dirt-collector tube rising from the upper end of the column into the bowl, and a supply-pipe passing through the column and having a branch extending laterally through the dirt-collector tube.

2. The combination of a bowl, a column in communication with the bottom thereof, a dirt-collector tube rising from the upper end of the column into the bowl, a supply-pipe passing through the column and having a branch extending laterally through the dirt-collector tube, a valve controlling the discharge of the said branch, a float operating the valve, and a shield inclosing the float.

3. The combination of a bowl, a column in communication with the bottom thereof, a dirt-collector tube rising from the upper end of the column into the bowl, a supply-pipe passing through the column and having a branch extending laterally through the dirt-collector tube, a valve controlling the discharge of the said branch, a float operating the valve, a shield inclosing the float, and means for heating the interior of the shield, for the purpose specified.

4. The combination of a bowl, a column communicating with the bottom thereof, a supply-pipe passing upward through the bottom, a dirt-collector tube fitted in the upper end of the column and rising above the same, and a conical foraminated cup for the dirt-collector tube.

5. The combination of a bowl, a heating-chamber extending around the same, a connection communicating with one end of the heat-

ing-chamber, the other end of the heating-chamber being adapted to have communication with the atmosphere, a case in communication with the connection and adapted to contain a heating means, and a tube passing from the upper portion of the bowl downward into communication with the atmosphere and having a branch leading into the said case.

6. The combination of a bowl having a heating-chamber therein, one end of said chamber being adapted to have communication with the atmosphere, a case adapted to contain a heating means and having communication with the other end of the heating-chamber, and a tube passing downward from the upper portion of the bowl into communication with the atmosphere and having a branch extending into the said case.

7. The combination of a bowl, a heating-chamber therein, a case having communication with the heating-chamber, a cover for the bowl, and a flue carried by said cover and having communication with the other end of the heating-chamber, for the purpose specified.

8. The combination of a bowl, a heating-chamber therein, a case having communication with the heating-chamber, a cover for the bowl, a flue carried by said cover and having communication with the other end of the heating-chamber, for the purpose specified, a float-shield attached to the cover and communicating with the flue thereof, a float located in said shield, a valve actuated by the float, and water-supply means controlled by the valve.

9. The combination of a bowl having a heating-chamber therein, a cover for the bowl, a flue carried by the cover and communicating with the atmosphere and with one end of the heating-chamber, and means for conducting a heated fluid to the other end of the heating-chamber.

10. The combination of a bowl, a dirt-col-

lector tube rising from the bottom thereof into the bowl, and a supply-pipe passed through said tube and having a lateral branch extending beyond the same into the bowl, through which branch the supply-tube discharges.

11. The combination of a bowl, a column communicating with the bottom thereof, a means for supplying water to the bowl, a dirt-collector tube fitted on the upper end of the column and projecting into the bowl, and a conical foraminated cap for the dirt-collector tube.

12. The combination of a bowl, a cover therefor, a flue carried by the cover and adapted to have communication at one end with means for supplying heated fluid to the flue, a float-shield attached to the cover and communicating with the other end of the flue, a float located in said shield, and means actuated by the float for controlling the water-supply to the bowl.

13. In a stock-waterer, the combination of a bowl, open at its top to permit the stock to drink therefrom, walls forming a heating-chamber extending completely around the sides of the bowl, said chamber communicating at one end with the atmosphere, a transversely-extending connection communicating with the other end of the heating-chamber and projecting beyond the same, a case or inclosure separate from the heating-chamber and bowl and located at one side thereof, and communicating with said connection, and a heating device located in the case or inclosure and adapted to supply heat to the interior of the heating-chamber.

In testimony whereof I have signed my name to this specification in the presence of two subscribing witnesses.
